ROTARY DRILLING APPARATUS

Joseph A. Dunn, Los Angeles, and Walter Elliot,
La Habra Heights, Calif.; said Dunn assignor
to The National Supply Company, a corpora-
tion of Pennsylvania

Application November 12, 1938, Serial No. 240,088

7 Claims. (Cl. 255—19)

This invention relates to rotary drilling apparatus of the type as used in the drilling of oil, gas, water, or other wells.

In the practice of rotary well drilling, it is common practice to employ a rotary machine positioned in the center of the derrick floor, which rotary machine is driven by a chain from one shaft of a drawworks situated at one side of the derrick floor. In this practice it is common to drive the drawworks and the rotary machine from a single engine or prime mover. With such an arrangement the chain from the drawworks shaft extends over the floor of the derrick to the rotary machine and forms an obstruction which hampers the free use of the floor and the free access to the rotary machine during the drilling operations.

It is therefore an object of our invention to provide an apparatus for the drilling of wells, which apparatus is so constructed and arranged as to permit the free and unobstructed use of the derrick floor and free and unobstructed access to the rotary machine during the drilling operations.

It is an object of this invention to provide an apparatus in which means are provided which are instantly available to drive the drawworks in an emergency.

Another object of our invention is to provide an apparatus for the drilling of wells in which there is provided an independent prime mover for the rotary machine which is not positioned upon the derrick floor.

Another object of our invention is to provide a rotary drilling rig having a rotary machine which is normally driven from a prime mover or engine situated below the derrick floor and in which there is provided an emergency drive which may be established above the derrick floor level for driving the rotary machine from the prime mover normally used to operate the drawworks.

Other objects and advantages of this invention it is believed will be apparent from the following detailed description of a preferred embodiment thereof as illustrated in the accompanying drawing.

In the drawing:

Figure 1 is a side elevation of a rotary drilling rig embodying our invention illustrating the same as adapted in position in the fragment of a drilling rig illustrated partly in section.

Figure 2 is a top plan view of the rotary drilling rig embodying our invention illustrating the same as detached from the derrick for clarity.

Figure 3 is a sectional view taken substantially on the line 3—3 of Figure 2.

In the preferred embodiment of our invention as illustrated in the drawing, 1 indicates a rotary machine which may be of any suitable or desirable type and which is driven through a driven sprocket carried by the shaft of the rotary machine. This rotary machine is, as is conventionally true, positioned in substantially the center of the derrick floor 3. Positioned at one side of the derrick floor is the rotary drawworks 4. The rotary drawworks is driven from a prime mover or engine 5 positioned to the rear of the drawworks, as is conventional. An auxiliary, or second, prime mover or engine 6 is positioned upon the foundation 7 below the derrick floor 3. The engines 5 and 6 may be of any suitable or desirable type or character and may constitute any form of prime mover or source of power, and it is intended that the word "engine" as hereinafter utilized in this specification and claims shall have such a generic definition.

The drawworks 4 may likewise be of any suitable or desirable type and as herein illustrated is of the form of a three-shaft drawworks, including a power or jack shaft 8 which is operatively connected through a transmission connection 9 with the engine 5.

The drawworks 4 likewise includes the customary drum shaft upon which the hoisting drum 10 is mounted. As is customary in this art there is formed between the power or jack shaft 8 and the drum shaft a multiple speed transmission means whereby the drum may be rotated at a plurality of speeds.

In the illustration given there is mounted in advance of the drawworks a shaft 11 which forms a countershaft for the transmission connections to or from the rotary drawworks 4, as will hereinafter be described.

The transmission drive 9 from the engine 5 to the jack shaft 8 includes a sprocket 12 which is journaled upon the jack shaft 8 and is releasably clutched thereto by means of a clutch indicated at 13. A sprocket 14 is journaled on the outer end of this shaft 8 and is likewise releasably connectable with the shaft 8 by means of a clutch 15. A transmission drive is provided including a chain 16 and sprocket 17 from the sprocket 14 to the double sprocket 17 carried upon the drum shaft. A transmission connection 18 is provided from the sprocket 17 to a double sprocket 19 mounted upon the shaft 11.

In accordance with our invention, the rotary machine sprocket 2 is normally driven from the

- engine situated below the derrick floor through a transmission chain 20 which connects from the sprocket 2 to a sprocket 21 carried upon a drive shaft 22 journaled in bearings 23 and 24 upon the frame 25 which likewise supports the engine 6. This shaft 22 is coupled to the engine shaft 25* by means of a coupling 26. The sprocket 21 is journaled upon the shaft 22 and provides the rotary machine drive sprocket. A second sprocket 27 providing a drawworks drive sprocket is likewise journaled upon the shaft 22.
- Clutch means 22 are provided for releasably clutching sprocket 21 to the shaft 22 when it is desired to drive the rotary machine from the engine 6.
- A clutch 29 is provided for releasably connecting the sprocket 27 to the shaft 22 when it is desired to drive the rotary drawworks 4 from the drilling engine 6. This drive is provided through a transmission chain 30 which connects with the one sprocket 31 of the double sprocket 19. Thus there is provided a standby, or emergency, drive for the rotary drawworks in the event of the hoisting engine 5 becoming incapacitated for any reason.
- In order to provide a means whereby the rotary machine 1 may be driven from the hoisting engine 5 should the drilling engine 6 for any reason become incapacitated, that is, to provide a standby or emergency power drive, there is provided a clutch means consisting of a clutch ring 32 which is splined upon the hub 33 of the sprocket 27 so that as the clutch ring 32 is shifted, its clutch jaws may engage corresponding clutch jaws 34 formed upon the hub of the sprocket 21. Thus with the clutches 13, 15 and 32 in engagement, the drive to the rotary machine is from the hoisting engine 5 through the corresponding transmission connections to the rotary machine drive sprocket 2, that is of course assuming that the clutches 28 and 29 are disengaged because of the fact that if the drilling engine 6 is incapacitated for any reason it is not desired to cause the engine 6 to be rotated during this method of driving.
- In order to control the engines 5 and 6 the controls for the two engines indicated at 35 and 36 drawworks 4 and in the position usually occupied by and adjacent the controls for operating the drawworks 4.
- In event the drilling engine 6 becomes incapacitated and it is not possible or practical under the particular conditions of operation to drive from the hoisting engine through the under-floor transmission system to the rotary machine, our invention permits the rotary machine 1 to be driven directly from the sprocket 17* of the double sprocket member 17 mounted on the drawworks drumshaft. This is accomplished by disconnecting the chains 28 and 18, and connecting a chain 37 directly from the sprocket 17* to the rotary machine drive sprocket 2 above the level of the floor 3, thus affording the conventional drive from the drawworks 4 to the rotary machine 1.
- The double sprocket units illustrated upon the floor shaft 11 and drum shaft, i. e., the sprockets 19 and 17, may be of the form or type as disclosed in the Rice and Morgan Patent No. 2,026,141, issued December 31, 1935.
- As is customarily provided in connection with such drilling apparatus, guards 38 and 39 are provided in connection with the sprockets 21 and 27 to form a substantially oil-tight enclosure and to prevent escape of lubricant from the chains and sprockets.

Having fully described our invention, it is to be understood that we do not wish to be limited to the details herein set forth, but our invention is of the full scope of the appended claims.

We claim:

1. In a well drilling rig having a drawworks and a rotary machine, the combination of a hoisting engine adapted to drive the drawworks, a shaft, transmission connections between the shaft and the rotary machine and between the shaft 10 and the drawworks, a drilling engine adapted to drive said shaft, clutch means associated with said transmission connections whereby said drilling engine may drive either the drawworks or the rotary machine independently of the hoisting 15 engine, and said hoisting engine being adapted to drive the rotary machine through said transmission connections independently of the drilling engine.
2. In a well drilling rig including a derrick 20 having a floor, the combination of a drawworks having a driveshaft, a rotary machine having a drive shaft, said drive shafts being in parallel relation, an intermediate shaft parallel to both drive shafts, a small capacity engine adapted 25 to drive said intermediate shaft, a large capacity engine adapted to drive said drawworks driveshaft, said rotary machine, drawworks, and large capacity engine being mounted near the level of the derrick floor, and said intermediate shaft and 30 said small capacity engine being mounted below the level of the derrick floor, transmission connections including a chain and sprocket drive between the intermediate shaft and the drive shaft of said rotary machine, and between the intermediate shaft and the drive shaft of said drawworks, and clutch means associated with said transmission connections whereby the small capacity engine may selectively drive either the rotary machine or the drawworks. 35
3. In a well drilling rig including a derrick having a floor, the combination of a drawworks having a driveshaft, a rotary machine having a drive shaft, said drive shafts being in parallel relation, an intermediate shaft parallel to both drive shafts, a small capacity engine adapted to drive said intermediate shaft, a large capacity engine adapted to drive said drawworks driveshaft, said rotary machine, drawworks, and large capacity engine being mounted near the level 40 of the derrick floor, and said intermediate shaft and said small capacity engine being mounted below the level of the derrick floor, transmission connections including a chain and sprocket drive between the intermediate shaft and the drive shaft of said rotary machine, and between the intermediate shaft and the drive shaft of said drawworks, and means including a clutch on said drawworks driveshaft whereby the large capacity engine may selectively drive the rotary 45 machine through said transmission connections. 50
4. In a well drilling rig including a derrick having a floor, the combination of a drawworks having a drum shaft and a drive shaft, a double idler sprocket member rotatably mounted on the 55 drumshaft, means to drivably connect one of the sprockets thereof to said drive shaft, a rotary machine having a pinion shaft, an intermediate shaft parallel to said drive shaft and said pinion shaft, a drilling engine adapted to drive said intermediate shaft, a hoisting engine adapted to drive said drive shaft, said drawworks, rotary machine and hoisting engine being mounted near the level of the derrick floor, and said intermediate shaft and said drilling engine being mount- 60 65 70 75 80 85 90

- ed substantially below the level of the derrick floor, transmission connections between said intermediate shaft and said pinion shaft, and between said intermediate shaft and the other 5 sprocket of said double idler sprocket member, and clutch means associated with said transmission connections whereby either engine may selectively drive the drawworks drumshaft or the rotary machine.
- 10 5. In a well drilling rig, the combination of a drawworks having a drive shaft, a rotary machine having a pinion shaft, an intermediate shaft parallel to both of said shafts, a large capacity engine adapted to drive said drive shaft, a small capacity engine adapted to drive said 15 intermediate shaft, a pair of sprockets independently rotatable on said intermediate shaft, individual clutch means for selectively coupling each sprocket in driving relation with the intermediate shaft, transmission connections from one of said sprockets to said rotary machine pinion shaft, and from the other of said sprockets to said drawworks driveshaft, whereby the small capacity engine may selectively drive either the 20 drawworks or the rotary machine, and additional clutch means for coupling said sprockets together to rotate as a single unit, whereby the large capacity engine may selectively drive the rotary machine through said transmission connections 25 independently of the intermediate shaft.
6. In a well drilling rig including a derrick having a floor, the combination of a drawworks, a rotary machine, a shaft operatively interposed between the drawworks and the rotary machine, a large capacity engine adapted to drive the drawworks, a small capacity engine adapted to 30 drive said shaft, said rotary machine, drawworks, and large capacity engine being mounted near the level of the derrick floor, and said shaft and said small capacity engine being mounted below the level of the derrick floor, a chain and sprocket 5 drive connecting said shaft and rotary machine, additional transmission driving connections between the shaft and the drawworks, and clutch means whereby said shaft may be operatively connected to selectively drive either the drawworks 10 or the rotary machine.
7. In a well drilling rig including a derrick having a floor, a rotary machine mounted centrally of said floor, a drawworks positioned at the floor level and at one side of the floor, and a 15 hoisting engine adapted to drive the drawworks, the combination of power transmission means disposed beneath said floor and operatively connecting said drawworks and rotary machine whereby the floor space between the drawworks 20 and the rotary machine is substantially unobstructed, said power transmission means including a shaft positioned below said floor and operatively interposed between the drawworks and the rotary machine, the shaft being connected 25 with said rotary machine and drawworks by means of chain and sprocket drives, a drilling engine positioned below said floor and adapted to drive said shaft, and clutch means associated with said power transmission means whereby the 30 drilling engine may selectively drive either the rotary machine or the drawworks independently of the hoisting engine.

CERTIFICATE OF CORRECTION.

Patent No. 2,192,584.

March 5, 1940.

JOSEPH A DUNN, ET AL.

It is hereby certified that error appears in the printed specification of the above numbered patent requiring correction as follows: Page 2, first column, line 12, for the reference numeral "22" read 28; line 47, after "35 and 36" insert are centralized at the position adjacent the; and that the said Letters Patent should be read with this correction therein that the same may conform to the record of the case in the Patent Office.

Signed and sealed this 9th day of April, A. D. 1940.
